(57) **CLAIM**

The ornamental design for a mobile device holder, as shown and described.

DESCRIPTION

FIG. 1 is a perspective view of a mobile device holder showing my new design;

FIG. 2 is a front view of the mobile device holder;

FIG. 3 is a rear view of the mobile device holder;

FIG. 4 is a left side view of the mobile device holder;

FIG. 5 is a right side view of the mobile device holder;

FIG. 6 is a top view of the mobile device holder; and,

FIG. 7 is a bottom view of the mobile device holder.

The dashed broken lines shown in FIGS. 1, 2 and 3 depict boundary lines of the claimed design and form no part thereof.

1 Claim, 4 Drawing Sheets
